LIQUID CONTAINING RESERVOIR OF A DRINK DISPENSING MACHINE

George Persak, Jr., Verona, N. J., assignor to The
Oiljak Manufacturing Co., Inc., Montclair,
N. J., a corporation of New Jersey

Application April 7, 1951, Serial No. 14,748

Term of patent 14 years

(Cl. D2—3)

To all whom it may concern:

Be it known that I, George Persak, Jr., a citizen of the United States, residing at Verona, in the county of Essex and State of New Jersey, have invented a new, original and ornamental Design for a Liquid Containing Reservoir of a Drink Dispensing Machine, of which the following is a specification, reference being had to the accompanying drawing, forming part thereof.

Fig. 1 is a perspective view of the liquid containing reservoir of a drink dispensing machine, embodying my new design;

Fig. 2 is a top plan view of the same;

Fig. 3 is a bottom plan view thereof; and

Fig. 4 is an enlarged broken vertical sectional view of the base portion of the reservoir.

I claim:

The ornamental design for a liquid containing reservoir of a drink dispensing machine, substantially as shown.

GEORGE PERSAK, JR.
